COMBUSTION CONTROL SYSTEM

Wayland R. Miller, Oconomowoc, Wis., assignor
to Minneapolis-Honeywell Regulator Company,
Minneapolis, Minn., a corporation of Delaware

Application July 1, 1937, Serial No. 151,399

8 Claims. (Cl. 236—14)

This invention relates to combustion control systems.

An object of this invention is to provide a new and improved method for controlling a furnace equipped with fuel supplying means and damper means to maintain the damper means closed during standby periods to prevent heat losses through the stack, to open wide the damper means when it is desired to operate the furnace for providing unobstructed draft through the furnace, to operate the fuel supplying means and ignite the fuel after the damper means is wide open, and to adjust the damper means to regulate the draft through the furnace after combustion has been actually established.

Another object of this invention is to provide an automatic control system for accomplishing automatically the above sequence of operation.

Other objects and advantages will become apparent to those skilled in the art upon reference to the accompanying specification, claims and drawing.

For a more thorough understanding of the invention reference is made to the accompanying single sheet of drawing in which there is diagrammatically shown the preferred form of this invention.

10 designates a boiler provided with a combustion chamber 11. The boiler is fired by means of an oil burner 12 in a conventional manner. The products of combustion may pass from the combustion chamber 11 over a bridge 13 to a back chamber 14 and thence through fire tubes 15 to a front chamber 16. The gases of combustion are drawn from the front chamber 16 through a breech or flue 17 which connects into a chimney or stack (not shown). Steam is generated around the fire tubes 15 and is collected in a drum 18. The steam passes from the drum 18 through a pipe 19 to a plurality of heat exchangers, one of which is shown at 20. The heat exchangers 20 may be utilized for heating a space or spaces. Condensed steam passes from the heat exchangers through a trap 21 and is returned to the boiler 10 in any suitable manner. An indirect heater 22 may be connected in the water space of the boiler to provide hot water for any desired use. Although I have shown a particular type of boiler for purposes of illustration it is to be understood that any other type of boiler may be utilized within the contemplation of this invention.

Fuel oil is supplied to the oil burner 12 by means of a pipe 25 leading from a source of fuel oil (not shown) and the flow of fuel oil through

the pipe 25 is controlled by an on and off valve 26 operated by a solenoid motor 27 of usual design and by a modulating valve 28. The modulating valve 28 may be operated through a pitman 29 by a crank disc 30 mounted on a shaft 31 of a motor 32. The motor 32 is preferably of the proportioning type and is adapted to modulate the valve 28 between a minimum position wherein a small flow of fuel oil is permitted and a maximum position wherein a large flow of fuel oil is permitted. The pitman 29 and the crank disc 30 are preferably arranged so that the proportioning motor 32 does not completely close the valve.

15 The proportioning motor 32 may comprise motor rotors 33 and 34 for rotating the shaft 31 through a reduction gear train 35. The motor rotors 33 and 34 are operated by field windings 36 and 37. The shaft 31 also operates a slider 38 with respect to a resistance element 39. The slider 38 and the resistance element 39 form a balancing potentiometer, the operation of which will be pointed out more fully hereafter. The shaft 31 also operates a cam 40 which in turn 20 operates a mercury switch 41. The arrangement is such that when the field winding 36 is energized the valve 28 is moved toward the minimum position, the slider 38 is moved toward the left and the cam 40 is moved toward a position to cause closing of the mercury switch 41. When the field winding 37 is energized the valve 28 is moved toward an open position, the slider 38 is moved toward the right and the cam 40 is rotated in a clockwise direction to open the switch 41. 25 The cam 40 is so arranged that the switch 41 is closed only when the valve 28 is in the minimum position as shown in the drawing.

30 The proportioning motor 32 is controlled by a relay generally designated at 43 and this relay 40 may comprise series connected relay coils 44 and 45 for operating a switch arm 46 with respect to contacts 47 and 48. The arrangement is such that when the relay coil 44 is energized more than the relay coil 45 the switch arm 46 is moved into engagement with the contact 47 and when the relay coil 45 is energized more than the relay coil 44 the switch arm 46 engages contact 48. When the relay coils 44 and 45 are equally energized the switch arm 46 is maintained spaced midway between the contacts 47 and 48. Power is supplied to the relay coils 44 and 45 by means of a step-down transformer 49. The secondary 45 50 of the step-down transformer is connected across the relay coils 44 and 45 and the primary 51 is connected across wires 52 and 53 which in

turn are connected to line wires 54 and 55 leading from a source of power (not shown). The transformer 49 is continuously energized and therefore power is at all times supplied to the relay coils 44 and 45. The energizations of the relay coils 44 and 45 are controlled by partially short-circuiting either or both of these coils in a manner well known in the art.

The operation of the oil burner 12 is controlled by a starter generally designated at 57 and this starter 57 may comprise a relay coil 58 for operating switch arms 59 and 62. When the relay coil 58 is energized the switch arms 59 and 62 are moved into engagement with contacts 60 and 63 respectively and when the relay coil 58 is deenergized the switch arms 59 and 62 are moved out of engagement with contacts 60 and 63 and the switch arm 59 is moved into engagement with contact 61 by means of springs, gravity or other means (not shown). The oil burner 12 is provided with an ignition transformer 64 for igniting in the usual manner the combustible mixture delivered by the oil burner 12.

The flow of combustion gases through the boiler 10 and therefore the draft within the boiler 10 is controlled by a draft or breeching damper 66. This damper 66 is operated by a link 67 and a crank 68 mounted on a shaft 69 of a motor 70. The motor 70 is shown to be a floating motor although any other type of motor may be utilized. The shaft 69 is operated through a reduction gear train 71 by motor rotors 72 and 73 which are in turn influenced by field windings 74 and 75 respectively. The arrangement is such that when the field winding 74 is energized the damper 66 is moved toward an open position and when the field winding 75 is energized the damper 66 is moved toward a closed position. The shaft 69 operates an abutment member 76 which is adapted to open limit switches 77 and 78 when the damper 66 is moved to an extreme closed position or an extreme open position respectively. The shaft 69 also operates a cam 79 which in turn positions a mercury switch 80. The cam 79 is so arranged that it moves the mercury switch 80 to a closed position only when the damper 66 is moved to a wide open position. At all other positions of the damper 66 the switch 80 is open.

The floating motor 70 is controlled by a relay 82 which may comprise series connected coils 83 and 84 for operating a switch arm 85 with respect to contacts 86 and 87. When the relay coil 83 is energized more than the relay coil 84 the switch arm 85 engages contact 86 and when the relay coil 84 is energized more than the relay coil 83 the switch arm 85 engages contact 87 as shown in the drawing. Power is supplied to the relay 82 by means of a step-down transformer 88 having a secondary 89 connected across the series connected relay coils 83 and 84 and a primary 90 connected by wires 91 and 92 across line wires 54 and 55. Power is therefore at all times supplied to the relay coils 83 and 84 and the energizations of the relay coils 83 and 84 are controlled by short-circuiting of the relay coils 83 and 84.

A static pressure regulator generally designated at 94 is adapted under certain conditions to position the floating motor 70 and this static pressure regulator may comprise a casing 95 enclosing a diaphragm 96. The underside of the diaphragm 96 is connected by a pipe 97 to the combustion chamber of the boiler 10. The diaphragm 96 carries an operating stem 98 and is

biased upwardly by a spring 99. The stem 98 operates a mercury switch 100 provided with a center electrode 101, a left electrode 102 and a right electrode 103. As shown in the drawing, 5 the damper 66 is closed and therefore the draft through the furnace is a minimum. The spring 99 therefore maintains the diaphragm 96 in its upper position so that the electrodes 101 and 103 are bridged. However, when the damper 66 is opened to increase the draft through the furnace the spring 99 is overcome and the diaphragm 96 moves downwardly to cause the mercury in the mercury switch 100 to bridge the electrodes 101 and 102.

The combustion control system may be placed in operation by means of a room thermostat designated at 105 and this thermostat may comprise a bellows 106 containing a volatile fluid for operating a mercury switch 107. Upon a decrease in space temperature the bellows 106 contracts to close the switch 107. The system may also be placed in operation by means of a temperature responsive controller 108 which may comprise a bellows 109 connected by a capillary tube 110 to a bulb 111 located in the water space of the boiler 10. The bulb and capillary tube preferably contain a volatile fluid so that upon a decrease in temperature the bellows 109 contracts to cause a switch 112 to close. Therefore the switch 112 is opened and closed in accordance with boiler water temperature and the switch 107 is opened and closed in accordance with room temperature. As will be pointed out more fully hereafter, these two switches are connected in parallel with respect to each other so that either may place the combustion control system in operation. The temperature responsive controller 108 therefore maintains the boiler water at a predetermined temperature to provide hot water for any desired purpose and to maintain the boiler water temperature just under the boiling point so that the time lag following a call for heat by the room thermostat 105 and the generation of steam is decreased to a minimum.

45 The oil burner 12 and its associated mechanism is controlled by an oil burner relay system which may comprise a relay generally designated at 114 and another relay generally designated at 115. The relay 114 comprises a relay coil 116 which when energized moves switch arms 117, 118, 119 and 120 into engagement with contacts 121, 122, 123 and 124 respectively. When the relay coil 116 is deenergized the switch arms are moved out of engagement with their respective contacts by means of springs, gravity or other means (not shown). Likewise the relay 115 comprises a relay coil 125 which when energized moves switch arms 126, 127 and 128 into engagement with contacts 129, 130 and 131 respectively. When the relay coil 125 is deenergized the switch arms are moved out of engagement with their respective contacts by means of springs, gravity or other means (not shown). Power is supplied to these two relays 114 and 115 by means of a step-down transformer 132 having a secondary 134 and a primary 135. The primary 135 is connected by a wire 136 to the line wire 55 and by a wire 137 through a mercury switch 138 operated by a low water cut off 139 and through a switch 140 operated by a high limit pressure controller 141 to the other line wire 54. The mercury switch 138 of the low water cut off 139 is moved to an open position in case the water level within the boiler is too 70 low. The high limit pressure controller may

comprise a bellows 142 connected by a pipe 143 to the pipe 19 and the arrangement is such that when the pressure in the pipe 19 and consequently in the boiler 10 becomes excessive the switch 140 is opened. Since the switches 138 and 140 are in series with the primary 135 of the step-down transformer 133, power is supplied to the transformer 133 only when the boiler water is at a safe level and the steam pressure is not excessive.

Associated with the oil burner relays 114 and 115 is a safety switch generally designated at 145 and this switch may comprise contacts 146 operated by a bimetallic element under the influence of a heater 147. The safety switch 145 may be of the type disclosed in F. S. Denison Patent No. 1,958,081, and therefore a further description is not considered necessary it being sufficient to state that when the heater 147 is energized for a given period of time the contacts 146 open and require manual resetting. Also associated with the oil burner relays 114 and 115 is a combustion responsive device generally designated at 148. This device may include a thermostatic element extending into the path of gases of combustion as at 149 for operating a switch arm 150 with respect to contacts 151 and 152. The switch arm 150 and the contacts 151 and 152 are so arranged

that they provide overlapping action upon a temperature increase. By this it is meant that when the thermostatic element is cold the switch arm 150 engages the contact 151 and as the thermostatic element increases in temperature the switch arm 150 engages the contact 152 before it disengages the contact 151. However, upon a decrease in temperature the switch arm 150 disengages the contact 152 before it reengages the contact 151. Such a construction is well known in the art and a further description thereof is not considered necessary.

The temperature responsive controller 108 and the room thermostat 105 control a relay generally designated at 154. This relay may comprise a relay coil 155, which when energized, moves switch arms 156 and 157 into engagement with contacts 158 and 159. When the relay coil 155 is deenergized the switch arms are moved out of engagement with their respective contacts and the switch arm 157 is moved into engagement with a contact 160 by means of springs, gravity or other means (not shown). Power is supplied to the relay 154 by means of step-down transformer 162 having a secondary 163 and a primary 164 connected across wires 136 and 137. It follows then that the transformer 162 is supplied with power as long as the water level in the boiler is normal and also the steam pressure in the boiler is normal.

A second combustion responsive switch is generally designated at 166 and may include a thermostatic element extending into the boiler in contact with the combustion gases as at 167 for operating a switch arm 168 with respect to contacts 169 and 170. When the thermostatic element is cold the switch arm 168 engages the contact 169 but when the thermostatic element is heated upon establishment of combustion the switch arm 168 engages the contact 170. A further description of this switching mechanism is not considered necessary since the construction thereof is known in the art.

A pressure responsive controller which, under certain conditions, positions the proportioning motor 32 is generally designated at 172 and this controller may comprise a bellows 173 suitably

connected to the steam pipe 19 for operating a slider 174 with respect to a resistance element 175. The slider 174 and the resistance element 175 form a control potentiometer for the proportioning motor 32. Upon an increase in pressure the slider 174 is moved upwardly and upon a decrease in pressure this slider is moved downwardly.

With the parts in the position shown in the drawing, the room thermostat 106 and the temperature responsive controller 108 are satisfied and therefore the control system is shut down. The valve 26 in the fuel supply line is closed and the valve 28 is in a minimum position. The oil burner is inoperative and the draft or breeching damper 66 is in a closed position to prevent the escape of heat from the boiler through the breech or flue 17 to the chimney. The draft or breeching damper 66 is in a closed position since the relay coil 83 of the relay 82 is short-circuited whereby relay coil 84 is energized more than relay coil 83 to maintain the switch arm 85 in engagement with the contact 87. Likewise the valve 28 is in a minimum position since the relay coil 45 is short-circuited by the switch arm 59 engaging the contact 61 of the starter 57.

Assume now that the space temperature decreases so as to close switch 107 of the room thermostat 105 or that the boiler water temperature decreases to such a value as to close switch 112 of the temperature responsive controller 108. A circuit is therefore completed from the secondary 163 through the switch 107 and relay coil 155 or through the switch 112 and relay coil 155 to cause energization of the relay coil 155. As a result switch arms 156 and 157 are moved into engagement with contacts 158 and 159. Movement of the switch arm 157 out of engagement with the contact 160 breaks the short circuit through the relay coil 83 and movement of the switch arm 156 into engagement with the contact 158 at this time has no effect. Movement of the switch arm 157 into engagement with the contact 159 completes a short-circuit for the relay coil 84 of the relay 82 extending from the junction of the relay coils 83 and 84 through switch arm 157, contact 159, switch arm 168 and cold contact 169 of the combustion responsive switching mechanism 166 and through a protective resistance to the right end of the relay coil 84. By reason of this the relay coil 83 becomes energized more than the relay coil 84 and the switch arm 85 is moved into engagement with the contact 86 to complete a circuit from the wire 91 through switch arm 85, contact 86, limit switch 78 and field winding 74 back to the other wire 92. Completion of this circuit energizes the field winding 74 to move the damper 66 towards an open position.

When the damper 66 is moved to an extreme open position the limit switch 78 is opened to break the circuit through the field winding 74 and the switch 80 operated by the cam 79 is closed. Closure of the switch 80 completes a circuit from the secondary 134 through safety switch contacts 146, mercury switch 80, mercury switch 41 operated by the proportioning motor 32, safety switch heater 147, relay coil 116, cold contact 151 of the combustion responsive switching mechanism 148 and switch arm 150 back to the secondary 134. Completion of this circuit causes heating of the heater 147 and energization of the relay coil 116. Energization of the relay coil 116 moves switch arms 117, 118, 119 and

120 into engagement with contacts 121, 122, 123 and 124.

Movement of the switch arm 117 into engagement with the contact 121 completes a maintaining circuit for the relay coil 116 which circuit may be traced from the secondary 134 of step-down transformer 133 through safety switch contacts 146, contact 158 and switch arm 156 of relay 154, contact 121 and switch arm 117 of relay 114, heater 147, relay coil 116, cold contact 151 and switch arm 150 back to the secondary 134. This maintaining circuit shunts out the switch 88 operated by the floating motor 78 and the switch 41 operated by the proportioning motor 32 and therefore the relay 114 may remain pulled in even though the draft damper 66 is moved away from the wide open position or the valve 28 is moved away from its minimum position. Summing up, in order to pull in the relay 114, both switches 88 and 41 operated by 20 the floating motor 78 and the proportioning motor 32 respectively must be closed, but after the relay 114 has once been pulled in it makes no difference whether these switches are opened or closed as long as the space thermostat 105 or 25 the temperature responsive controller 108 are calling for heat.

Movement of the switch arm 119 into engagement with contact 123 completes a circuit from the wire 137 through contact 123, switch arm 119, relay coil 58 and solenoid motor 27 which are connected in parallel back to the wire 138. Therefore, when the relay 114 pulls in the valve 26 is opened and the relay coil 58 is energized to move switch arms 59 and 62 into engagement with contacts 66 and 63 respectively. Movement of the switch arm 62 into engagement with the contact 63 completes a circuit from wire 52 through switch arm 62, contact 63 and oil burner motor back to the wire 53. The oil burner motor is therefore placed in operation to supply a combustible mixture to the boiler 10. Movement of the switch arm 59 out of engagement with the contact 61 breaks the short circuit for the relay coil 45 and movement of the switch arm 59 into engagement with the contact 60 connects the junction of the relay coils 44 and 45 with the slider 174 and places the relay 48 under the control of the pressure controller 172. The proportioning motor 32 and consequently the valve 28 will be moved to a position corresponding to the position of the slider 174 of the control potentiometer and since this slider 174 is positioned in accordance with variations in steam pressure the motor 32 and consequently the valve 28 will be positioned in accordance with variations in steam pressure. As the steam pressure decreases the slider 174 moves downwardly to decrease the energization of the relay coil 44 and increase the energization of the relay coil 45 to move the switch arm 46 into engagement with the contact 48. This completes a circuit from the wire 52 through switch arm 46, contact 48 and field winding 37 back to the other wire 53. The valve 28 is therefore moved toward an open position. As the valve is moved toward an open position the slider 38 is moved toward the right to decrease the energization of the relay coil 45 and increase the energization of the relay coil 44. When the slider 38 has moved sufficiently far to the right to rebalance the energizations of the relay coils 44 and 45, the switch arm 48 is moved out of engagement with the contact 48 to break the circuit through the field winding 37. In this

5 manner the valve 28 is modulated toward an open position in accordance with the amount of decrease in steam pressure. Conversely, an increase in steam pressure causes upward movement of the slider 174 to decrease the energization of the relay coil 45 whereupon the switch arm 48 is moved into engagement with the contact 47 to complete a circuit through the field winding 38. This causes movement of the valve 28 towards a closed position and also left hand movement of the slider 38. This left hand movement of the slider 38 decreases the energization of the relay coil 44 and increases the energization of the relay coil 45 and when the slider 38 has moved sufficiently far to the left so as to rebalance the energization of the relay coils 44 and 45 the switch arm 48 is moved out of engagement with the contact 47 to break the circuit through the field winding 38. It follows then that when the switch arm 59 of the starter 57 engages the contact 61, the valve 28 is maintained in a minimum position but when the starter 57 is pulled in to move the switch arm 59 into engagement with the contact 60, the pressure responsive controller 172 modulates the valve 28 in accordance with variations in steam pressure. Therefore the supply of fuel to the oil burner 12 is increased as the steam pressure decreases and the supply of fuel is decreased as the steam pressure increases in order to maintain a substantially constant steam pressure during operation of the system.

Movement of the switch arm 120 of the relay 114 into engagement with the contact 124 completes a circuit from the wire 137 through contact 122, switch arm 119, switch arm 120, contact 124 and ignition coil 64 back to the wire 138. A combustible mixture is therefore supplied to the boiler 10 and is ignited. In case this combustible material is not ignited within a predetermined time the heater 147 causes opening 40 of the safety switch contacts 46 to cause the relay 114 to drop out to stop further operation of the oil burner 12, the ignition transformer 64 and 45 also to close the valve 28 and to move the valve 28 to a minimum position.

If, however, combustion is established the switch arm 150 of the combustion responsive switching mechanism 148 moves into engagement 50 with the contact 152 to complete a circuit from the secondary 134 through safety switch contact 146, contact 158, switch arm 156, contact 121, switch arms 117 and 118, contact 122, relay coil 125 of relay 115, hot contact 152 of the combustion responsive switching mechanism 148, and switch arm 150 back to the secondary 134. Completion of this circuit energizes the relay coil 125 to move the switch arms 126, 127 and 128 into engagement with the contacts 129, 130 and 131. Movement of the switch arm 126 into engagement with the contact 129 completes a maintaining circuit for the relay coil 125 which is independent of the contacts of the relay 114 and this maintaining circuit may be traced from the secondary 134 through safety switch contacts 146, contact 158, switch arm 156, contact 129, switch arm 126, relay coil 125, hot contact 152 and switch arm 150 back to the secondary 134. Movement of the switch arm 127 into engagement with the contact 130 completes a shunt circuit around the heater 147 of the safety switch and this shunt circuit extends through the relay coil 116 of the relay 114. This circuit may be traced from the secondary 134 through safety

switch contacts 146, contact 158, switch arm 156, contact 129, switch arms 126 and 127, contact 130, relay coil 116, cold contact 151 and switch arm 150 back to the secondary 134. This circuit maintains the relay coil 116 energized and shunts out the heater 147 whereupon opening of the safety switch contacts 146 is prevented.

A second circuit for the relay coil 58 of the starter 57 and the solenoid motor 27 is completed when the switch arm 128 engages the contact 131 and this second circuit may be traced from the wire 137 through contact 131, switch arm 128, solenoid motor 27 and relay coil 58 which are connected in parallel back to the wire 136. This circuit is entirely independent of the relay 114.

When the thermostatic element of the combustion responsive switching mechanism 148 becomes sufficiently heated to separate the switch arm 150 and the cold contact 151 all circuits through the relay coil 116 and the heater 147 are broken and the relay 114 drops out. As a result switch arm 120 disengages the contact 124 to break the circuit through the ignition transformer 64 whereupon ignition is terminated after combustion has been satisfactorily established. In this manner the solenoid valve 26 is maintained opened and the oil burner 12 is maintained in operation until such time as both the space thermostat 105 and the temperature responsive controller 108 are satisfied. When this occurs the relay 154 drops out and since switch arm 158 thereupon disengages contact 158 the relay 115 will drop out to stop the oil burner 12 and close the valve 26. The oil burner 12 and the valve 26 cannot again be placed in operation until such time as the thermostatic switching mechanism 148 has cooled sufficiently to move the switch arm 150 into engagement with the contact 151.

When combustion has been established in the manner pointed out above the switch arm 168 of the combustion responsive switching mechanism 166 is moved out of engagement with the contact 169 and into engagement with the contact 170. Movement of the switch arm 168 out of engagement with the contact 169 breaks the short-circuit through the relay coil 84 and movement of the switch arm 168 into engagement with the contact 170 connects the junction of the relay coils 83 and 84 to the center electrode 101 of the pressure regulator 94. The relay coils 83 and 84 of the relay 82 are thereupon connected to the electrodes 101, 102 and 103 of the pressure regulator 94. Upon a decrease in furnace pressure as the result of an increase in furnace draft the electrodes 101 and 102 of the pressure regulator 94 are bridged to complete a short-circuit for the relay coil 83 to decrease the energization thereof and increase the energization of the relay coil 84. This causes movement of the switch arm 85 into engagement with contact 87 to complete a circuit from the wire 91 through switch arm 85, contact 87, limit switch 11 and field winding 75 back to wire 92. This causes energization of the field winding 75 to move the damper 66 towards a closed position to decrease the draft through the boiler 10. Conversely, when the pressure in the boiler 10 increases as the result of a decrease in draft the electrodes 101 and 103 are bridged to complete a short-circuit for the relay coil 84 whereupon the switch arm 85 engages the contact 86 to complete a circuit from the wire 91 through switch arm 85, contact 86, limit switch 78 and field winding 74

5 back to the wire 92. This causes opening movement of the damper 66 to increase the draft through the furnace. By reason of this arrangement a floating control of the draft or breeching damper 66 is obtained to maintain the draft through the furnace substantially constant.

Assume now that both the space thermostat 105 and the temperature responsive controller 108 are satisfied, the relay 154 drops out and as a result the relay coil 83 is short-circuited by the switch arm 157 engaging the contact 160 and the draft damper 66 is thereupon moved to a complete closed position. Also as a result of dropping out of the relay 154 the oil burner 12 is stopped and the valve 26 in the fuel line is closed. The valve 28 is moved to a minimum position by engagement of the switch arm 59 of the starter 57 with contact 61. The parts are therefore returned to the position shown in the drawing.

Summarizing briefly, the sequence of operation is as follows: when there is no call for heat by either the space thermostat 105 or the temperature responsive controller 108 the oil burner 12 is inoperative, the ignition transformer 64 is inoperative, the on and off valve 26 is closed and the modulating valve 28 is in a minimum position. Also the draft or breeching damper is in a closed position to prevent losses to the stack, sometimes termed "standby" losses. When either the temperature responsive controller 108 or the space thermostat 105 calls for heat the relay 154 is pulled in and the draft or breeching damper 66 is moved to a wide open position. When the damper 66 moves to the wide open position, the oil burner 12 and the ignition transformer 64 are operated and the valve 26 is opened providing the modulating valve 28 is in minimum position. This proviso is extremely beneficial since in large installations it is not desirable to start up an oil burner with too large a flow of fuel oil since serious explosions may occur. When the oil burner 12 is placed in operation the proportioning motor 32 which positions the modulating valve 28 is placed under the control of the pressure controller 172 and the valve 28 is modulated in accordance with variations in steam pressure to maintain the steam pressure substantially constant when the system is in operation. As soon as the oil burner 12 is placed in operation a maintaining circuit for the oil burner 12 is established, which maintaining circuit is in parallel with the switch 80 operated by the floating motor 70 and the switch 41 operated by the proportioning motor 32. Therefore the oil burner 12 may be maintained in operation even though the draft damper 66 is moved away from the wide open position or the valve 28 is moved from the minimum position.

60 After combustion has accordingly been established the draft damper 66 is moved out of the wide open position and placed under the control of the pressure regulator 94 to maintain the draft through the boiler 10 substantially constant whereby the system operates most efficiently. 65 When the system is operating, the draft through the boiler 10 is maintained substantially constant and the fuel supply to the oil burner 12 is modulated in accordance with the variations in steam pressure. When the space temperature becomes satisfied and when the temperature responsive controller 108 becomes satisfied the oil burner is stopped, the valve 26 is closed, the valve 28 is returned to its minimum position, and the draft or breeching damper 66 is moved to a closed position.

Since in starting the system the valve 28 is in the minimum position, a large supply of fuel cannot be supplied to the oil burner 12 when the oil burner 12 is started up, since it is impossible to start the oil burner 12 until the breeching damper 66 is wide open and since it is impossible to place the breeching damper 66 under automatic control until combustion has been actually established, an extremely safe mode of operation is provided. The provision of the low water cut off 139 and the high pressure controller 141 which shut down the system during abnormal water level and steam pressure conditions also adds to the safety of the system.

Since the fuel supply to the oil burner 12 is modulated in accordance with the load on the boiler, since the draft damper 66 is positioned in accordance with the draft through the boiler when the system is operating and since the draft damper 66 is closed when the system is out of operation an extremely efficient mode of operation is provided. These features when taken in combination with each other form a control system which gives safe and efficient control of a boiler.

Although for purposes of illustration I have shown one form of my invention, other forms thereof may become apparent to those skilled in the art upon reference to this specification and therefore this invention is to be limited only by the scope of the appended claims and prior art.

I claim:

1. In a control system for a furnace having fuel supplying means and damper means, the combination of, control means for moving the damper means to a wide open position to provide unobstructed draft through the furnace, means associated with the damper means for starting operation of the fuel supplying means and igniting the fuel when the damper means reaches a wide open position, means for maintaining the fuel supplying means in operation even though the damper means is moved away from the wide open position, means for controlling the damper means in accordance with the draft through the furnace, and means responsive to the establishment of combustion in the furnace for placing the damper means under control of the draft responsive control means.

2. In a combustion control system, in combination, means forming a combustion chamber, means comprising a first valve and a second valve in series therewith for controlling a supply of fuel for the combustion chamber, said first valve having a minimum open position, switch means associated with said first valve, said switch means being closed when said first valve is in minimum position, control apparatus comprising means for causing said second valve to open provided said switch is closed and means responsive to the establishment of combustion of fuel supplied by said valves for completing an electrical circuit whereby said second valve remains open independently of said switch.

3. In a combustion control system, in combination, a combustion chamber having damper means controlling the eduction of gases therefrom, fuel supply control means and automatic means for initiating operation of the system, control means responsive to said automatic means for closing said damper means when the system is shut down and for opening said damper means wide open when operation of the system is to begin, draft responsive means for variably adjusting said damper means during operation,

and supervisory combustion responsive control means associated with said automatic means and control means whereby said draft responsive means are in active control during the progress of combustion and in the absence of combustion during a demand for operation of the system said control means are in control for maintaining said damper means wide open responsively to said automatic means.

10 4. In a combustion control system, in combination, a combustion chamber having damper means controlling the eduction of gases therefrom, fuel supply control means and automatic means for initiating operation of the system, control means responsive to said automatic means for closing said damper means when the system is shut down and for opening said damper means wide open when operation of the system is to begin, means associated with said damper means whereby operation of said fuel supply control means is dependent upon said damper means being in wide open position, draft responsive means for variably adjusting said damper means during operation, and supervisory combustion responsive control means associated with said automatic means and control means whereby said draft responsive means are in active control during the progress of combustion and in the absence of combustion during a demand for operation of the system said control means are in control for maintaining said damper means wide open responsively to said automatic means.

15 5. In a combustion control system, in combination, a combustion chamber having damper means controlling the eduction of gases therefrom, fuel supply control means and automatic means for initiating operation of the system, control means responsive to said automatic means for closing said damper means when the system is shut down and for opening said damper means wide open when operation of the system is to begin, means associated with said damper means whereby operation of said fuel supply control means is dependent upon said damper means being in wide open position, draft responsive means for variably adjusting said damper means during operation, supervisory combustion responsive control means associated with said automatic means and control means whereby said draft responsive means are in active control during the progress of combustion and in the absence of combustion during a demand for operation of the system said control means are in control for maintaining said damper means wide open responsively to said automatic means.

20 6. In a combustion control system, in combination, means forming a combustion chamber, means comprising a first valve and a second valve in series therewith for controlling a supply of fuel for the combustion chamber, said first valve having a minimum open position, switch means associated with said first valve, said switch means being closed when said first valve is in minimum position, control apparatus comprising means for causing said second valve to open provided said switch is closed, means responsive to the establishment of combustion of fuel supplied by said valves for completing an electrical circuit whereby said second valve remains open independently of said switch, means for variably adjusting said first valve and means whereby

said adjusting means actively controls said first valve in response to establishment of combustion.

7. In a combustion control system, in combination, means forming a combustion chamber, means comprising a first valve and a second valve in series therewith for controlling a supply of fuel for the combustion chamber, said first valve having a minimum open position, switch means associated with said first valve, said switch means being closed when said first valve is in minimum position, control apparatus comprising means for bringing about opening of said second valve and operating said system provided said switch means are closed, and means responsive to a condition within the combustion space produced as an incident to starting of the system and dependent upon said switch having been closed for completing an electrical circuit whereby said second valve is rendered independent of said switch.

5 8. In a combustion control system, in combination, means forming a combustion chamber, means comprising a first valve and a second valve in series therewith for controlling a supply of fuel for the combustion chamber, said first valve having a minimum open position, switch means associated with said first valve, said switch means being closed when said first valve is in minimum position, air flow varying means, control apparatus for bringing about operation of said air flow varying means, and for bringing about opening of said second valve provided said switch means are initially closed, said control apparatus including means responsive to operation of said air flow varying means for producing an operating condition in said combustion space, and means responsive to said condition for rendering said second valve independent of said switch means.
